UNITED STATES PATENT OFFICE.

BOWIE DASH, OF NEW YORK, N. Y.

DESIGN FOR ORNAMENTATION OF PAPER.

SPECIFICATION forming part of Design No. 15,087, dated June 24, 1884.

Application filed April 26, 1884. Term of patent 14 years.

To all whom it may concern:

Be it known that I, BOWIE DASH, a citizen of the United States, residing at New York, in the county and State of New York, have 5 invented a Design for the Ornamentation of Paper, &c., of which the following is a specification.

The invention relates to a design for the ornamentation of paper, &c.; and it consists in the representation of a bed of coffee-beans, the same having the appearance of beans carelessly thrown in mass upon the surface of the paper, and showing the individual beans, some of them lying upon and overlapping each 15 other, while others are represented as showing their rounded backs, and still others as

showing their creased faces or their sides, as if in elevation, the whole being intermixed and presenting the appearance of a solid bed of coffee-beans, as shown in the accompanying fac-simile.

What I claim as new is—

The design herein shown and described, the same consisting in the representation of a field upon paper, comprising the overlapping and intermingled coffee-beans in a solid bed.

Witness my hand this 21st day of April, A. D. 1884.

BOWIE DASH.
